UNITED STATES PATENT OFFICE.

WILSON L. CAMPBELL, OF CHICAGO, ILLINOIS, ASSIGNEE, BY MESNE ASSIGNMENTS, TO
AUTOMATIC ELECTRIC COMPANY, A CORPORATION OF ILLINOIS.

AUTOMATIC PARTY-LINE TELEPHONE SYSTEM.

1,329,287.

Specification of Letters Patent. Patented Jan. 27, 1920.

Application filed July 31, 1906, Serial No. 323,543. Renewed June 21, 1919. Serial No. 305,919.

To all whom it may concern:

Be it known that I, WILSON L. CAMPBELL, a citizen of the United States of America, and resident of Chicago, Cook county, Illinois, have invented a certain new and useful Improvement in Automatic Party-Line Telephone Systems, of which the following is a specification.

My invention relates to automatic telephone systems in general, and more particularly to telephone exchange systems in which selectors and connectors, or other suitable automatic switching machines, are located at the exchange or central station and controlled by calling subscribers for automatically connecting their telephone lines with the lines of the called subscribers, and especially to automatic exchange systems of this character in which subscribers' party lines are employed, necessitating the automatic removal of the guarding potentials when any party line subscriber calls another subscriber on the same line—that is to say, necessitating the automatic removal of the guarding potential which is ordinarily employed for preventing seizure of the calling line by other subscribers, thus permitting a party line subscriber to call back on his own line, so to speak.

Generally stated the object of my invention is the provision of an improved and highly efficient automatic party line telephone system.

Special objects of my invention are the provision of improved means for enabling a party line subscriber to automatically call and obtain connection with another subscriber's station on the same line; the provision of improved means for automatically removing the guarding potential established over the private normal of a calling party line, thus preventing the automatic release of the connector when it seizes the calling line—which is also, of course, the called line, inasmuch as it belongs as well to the called subscriber—the said connector having provisions for establishing such a guarding potential as will preclude seizure of the party line while the two subscribers thereon are conversing; and the provision of certain details and novel features of improvement and combinations tending to increase the general efficiency and serviceability of an automatic telephone exchange system of this particular character.

To the foregoing and other useful ends, my invention consists in matters hereinafter set forth and claimed.

In the accompanying drawings, Figure 1 is a diagrammatic representation of a party line terminating at the central office in a selector A, which selector is suitably connected to the battery B, and which party line comprises the substations C, D and E, showing the selector A connected with the connector F, the subscriber C having called the subscriber D, the system involving the principles of my invention.

Fig. 2 is a diagrammatic perspective view of the first-selector. 70

Fig. 3 is a similar view of the connector.

The substation may be of any suitable or approved type. The selector A is of the general type shown in Patent No. 815,321, or of any other suitable type. 75

The connector F may also be of any suitable or approved type, and the one herein shown is an improved connector of the general type described in Patent No. 815,176.

The selector is provided, in addition to the parts well known, with an improved bridge-cut-off-relay 2. Said relay has one terminal permanently connected to the battery B, while the other terminal is connected to the side switch private wiper contact 3 and with the winding 4 of the private normal relay 5. The said bridge-cut-off-relay 2 is provided with four springs 6, 7, 8 and 9. The springs 8 and 9 control the circuit between the vertical line relay 10 and the battery B, and the springs 6 and 7 control the connection between the switch shaft spring 11 and the rotary line relay 12 and, therefore, between the rotary line conductor 13 and the rotary line relay 12 whenever the switch shaft springs 11 and 14 are in contact. The bridge-cut-off-relay is adapted to be energized whenever the selector A calls back on its own line, or when some other subscriber calls the line to which the said selector is allotted. The private normal relay 5 is provided with two windings 4 and 15. One of the terminals of the winding 15 is permanently connected with the battery B and the other terminal is connected with the spring 17 of the rotary line relay 12, so that the relay 5 is adapted to be energized whenever the rotary line relay 12 presses the spring 17 onto the ground spring 18. The winding 4 of the private normal relay 110

has one terminal connected with the bridge-cut-off-relay 2 and the other terminal is connected to the spring 19 controlled by the relay 5 itself. The said relay 5 also controls 5 two other springs 20 and 21, and the spring 20, it will be noticed, is connected with the private normal conductor 22. Under certain conditions the springs 19 and 20 are brought into contact by the private normal 10 relay 5 while the private normal conductor 22 is grounded, and at such time the private normal relay 5 and the bridge-cut-off-relay 2 are energized in series. This, however, occurs only when one of the subscribers of the 15 party line calls back on his own line. Normally, the springs 20 and 21 are in contact, so that the private normal conductor 22 is maintained in connection with the bridge-cut-off-relay 2, and so that when a subscriber 20 calls in upon the line allotted to the selector A, he energizes the bridge-cut-off relay 2 at the selector by grounding the private normal conductor 22 at the connector. The selector is, of course, in addition provided 25 with the usual vertical magnet 23, rotary magnet 24, release magnet 25, switch-shaft 26, double dog 27, private bank 28, line bank 29, private wiper 30 and line wipers 31 and 32. The vertical magnet 23 controls the vertical 30 movement of the shaft 26, and the rotary magnet 24 the rotary movement of the said shaft. The private magnet 16 controls the side switch H and certain circuits, such as the release circuit and the circuit of the 35 vertical magnet 23.

The substation, as shown at C, is provided with the usual receiver 33, transmitter 34, battery 35, induction-coil 36, switch-hook 37, ringer 38, condenser 39, lock-out relay 40, 40 and calling device of any suitable type but which is here shown comprising the buttons 41 and 42, springs 43 and 44, contact points 45 and 46 and ground post 47. There are also provided, of course, the release springs 48, 49 and 50 and other details essential to an automatic telephone adapted to be used in a system of this kind. It will be understood that all of the substations are alike, and throughout the drawings like reference 50 characters will refer to like parts.

The connector F herein shown has a vertical line relay 51, a rotary line relay 52, a vertical magnet 53, rotary magnet 54, release-magnet 55, private magnet 56, and 55 ringer relay 57. The switch-shaft 58 is as usual provided with the private wiper 59 and the line wipers 60 and 61, which former is adapted to engage the private bank 62 and the latter wipers the line bank 63. The 60 connector F also has a vertical back-bridge relay 147 and a rotary back-bridge relay 148, the function of which will be fully described.

It will be assumed that the substation C is 65 #120, substation D #220 and substation E #320, and that the subscriber at substation C in calling the subscriber #220 at substation D operates the calling device three times, once for the first digit 2, once for the second digit 2 and once for the third 70 digit 0. The subscriber removes his receiver from the switch-hook 37 and thereby causes the ground springs 64 and 65 to close connection and thereby place the ground post 47 in connection with the ground terminal G of the battery B by way of the substation ground G¹, and at the same time he removes the ringer 38 from across the line when the switch-hook cam arm 66 leaves the spring 67. Furthermore, the secondary circuit comprising the receiver 33 and secondary winding 68 of the induction-coil is bridged across the line when the springs 69 and 70 are brought into contact. The subscriber then proceeds by pressing 75 the signaling button 41 twice, causing it each time to leave the contact point 45 and to engage the ground post 47. The vertical line relay 10 of the first-selector A is thereby energized twice. The energizing circuit 80 may be traced from ground G¹ to the ground post 47, thence over the vertical line conductor 71 and conductor 72 to the vertical line relay 10, thence through the bridge-cut-off relay springs 8 and 9 to the battery 85 lead 73 and through battery B to ground G. The vertical line relay 10, therefore, attracts its armature twice and forces the spring 74 onto the ground spring 18, thus energizing in turn each time the vertical 90 magnet 23. The circuit through said magnet permits a current to flow from ground G² through the springs 18 and 74, conductor 75, private springs 76 and 77, conductor 78, side switch wiper 79, contact point 80 to the vertical magnet 23, thence to the battery lead 73 and through battery B to ground G. The vertical line relay 10, therefore, attracts its armature twice and forces the spring 74 onto the ground spring 18, thus energizing in turn each time the vertical 95 magnet 23. The circuit through said magnet permits a current to flow from ground G² through the springs 18 and 74, conductor 75, private springs 76 and 77, conductor 78, side switch wiper 79, contact point 80 to the vertical magnet 23, thence to the battery lead 73 and through battery B to ground G. The vertical line relay 10, therefore, attracts its armature twice and forces the spring 74 onto the ground spring 18, thus energizing in turn each time the vertical 100 magnet 23. The circuit through said magnet permits a current to flow from ground G² through the springs 18 and 74, conductor 75, private springs 76 and 77, conductor 78, side switch wiper 79, contact point 80 to the vertical magnet 23, thence to the battery lead 73 and through battery B to ground G. The vertical line relay 10, therefore, attracts its armature twice and forces the spring 74 onto the ground spring 18, thus energizing in turn each time the vertical 105 magnet 23. The circuit through said magnet permits a current to flow from ground G² through the springs 18 and 74, conductor 75, private springs 76 and 77, conductor 78, side switch wiper 79, contact point 80 to the vertical magnet 23, thence to the battery lead 73 and through battery B to ground G. The vertical line relay 10, therefore, attracts its armature twice and forces the spring 74 onto the ground spring 18, thus energizing in turn each time the vertical 110 magnet 23. The circuit through said magnet permits a current to flow from ground G² through the springs 18 and 74, conductor 75, private springs 76 and 77, conductor 78, side switch wiper 79, contact point 80 to the vertical magnet 23, thence to the battery lead 73 and through battery B to ground G. The vertical line relay 10, therefore, attracts its armature twice and forces the spring 74 onto the ground spring 18, thus energizing in turn each time the vertical 115 magnet 23. The circuit through said magnet permits a current to flow from ground G² through the springs 18 and 74, conductor 75, private springs 76 and 77, conductor 78, side switch wiper 79, contact point 80 to the vertical magnet 23, thence to the battery lead 73 and through battery B to ground G. The vertical line relay 10, therefore, attracts its armature twice and forces the spring 74 onto the ground spring 18, thus energizing in turn each time the vertical 120 magnet 23. The circuit through said magnet permits a current to flow from ground G² through the springs 18 and 74, conductor 75, private springs 76 and 77, conductor 78, side switch wiper 79, contact point 80 to the vertical magnet 23, thence to the battery lead 73 and through battery B to ground G. The vertical line relay 10, therefore, attracts its armature twice and forces the spring 74 onto the ground spring 18, thus energizing in turn each time the vertical 125 magnet 23. The circuit through said magnet permits a current to flow from ground G² through the springs 18 and 74, conductor 75, private springs 76 and 77, conductor 78, side switch wiper 79, contact point 80 to the vertical magnet 23, thence to the battery lead 73 and through battery B to ground G. The vertical line relay 10, therefore, attracts its armature twice and forces the spring 74 onto the ground spring 18, thus energizing in turn each time the vertical 130 magnet 23. The circuit through said magnet permits a current to flow from ground G² through the springs 18 and 74, conductor 75, private springs 76 and 77, conductor 78, side switch wiper 79, contact point 80 to the vertical magnet 23, thence to the battery lead 73 and through battery B to ground G.

the springs 18 and 17, conductors 81 and 82 to the private magnet 16, thence to the battery lead 73 and through battery B to ground G. When the private magnet 16 operates, the side switch retracting spring 83 draws the side switch into second position, when the escapement finger 84 clears the escapement teeth 85 and 86. When the side switch passes to second position the 10 side switch wiper 87 engages the contact point 88 and an energizing circuit is then established for operating the rotary magnet 24. The current flows from ground G³ to the contact point 88, thence through the 15 side switch wiper 87, conductor 89 and through the rotary magnet 24 and interrupter springs 90 and 91 to the battery lead 73, thence through battery B to ground G. The rotary magnet upon attracting its armature 92 rotates the shaft 26 one step and drives the private wiper 30 into engagement with the first contact of the second level of the private bank 28. If the first trunk line is busy the rotary magnet 24 continues to 20 operate step by step until an idle trunk line is found, and if the first trunk line is busy the first private contact will be grounded and the private magnet 16 will become energized by a flow of current from the battery 25 B to the grounded private contact, thence through the private wiper 30, side switch wiper 93, contact point 94, conductors 95 and 82 to the private magnet 16, thence through the battery lead 73 and through 30 battery B to ground G. Obviously, the private magnet will, therefore, attract its armature and retain the side switch H locked in second position, maintaining the side switch 87 on the contact point 88. The 35 rotary magnet 24 being provided with the interrupter mechanism that comprises the interrupter springs 90 and 91 and the interrupter finger 96 will continue to operate step by step in a well known manner. As 40 soon as the private wiper 30 reaches a non-grounded contact the energizing circuit for the private magnet 16 is broken and the side switch H is drawn into third position by the retracting spring 83. When the side 45 switch passes to third position the subscriber's line conductors 71 and 13 are extended through the side switch wipers 97 and 98 to the line wipers 31 and 32 and thence to the trunk conductors 99 and 100 that lead to the connector F, as shown in 50 Fig. 1. The private wiper 30 connects at the same time with the trunk release conductor 101. It is assumed, of course, for the purpose of illustration, that all of the first 55 nine trunks are busy. When the side switch wiper 93 passes to third position it engages the grounded contact point 118 and as a result establishes a guarding potential at the connector private banks from the ground 60 terminal G⁸ by way of the private normal 65

conductor 22. The connection is made from the ground terminal G⁸ to the contact point 118, side switch wiper 93 to the private normal relay spring 21, thence to the spring 20 and to the private normal conductor 22. 70 It will be seen that when the rotary line relay 12 presses the springs 17 and 18 together not only is an energizing circuit established through the private magnet 16, but also through the winding 15 of the 75 private normal relay 5. The current through this winding passes from ground G² through the springs 18 and 17 and conductor 81 to the winding 15 of the private normal relay 5, thence through the battery lead 73 and 80 through battery B to ground G. Each time that the said relay 5 is energized a guarding potential from the ground G⁸ to the connector private bank is interrupted, but this is of no importance. Having obtained 85 connection with the connector-switch F the subscriber presses the button 41 twice and again grounds the vertical line conductor 71 twice. As a result the vertical line relay 51 of the connector is energized twice by a 90 flow of current from the substation ground terminal G¹ to the vertical line conductor 71, thence through the side switch wiper 97 to the contact point 102, conductor 103, line wiper 31, trunk conductor 99, vertical 95 line relay 51 to the battery lead 73 and through battery B to ground G. Of course the vertical line relay 10 of the first-selector A is also energized over the same circuits that have been described heretofore; but the 100 energization of this relay 10 has no significance at this time. The vertical line relay 51 upon attracting its armature twice presses the springs 104 and 105 into contact twice, and as a result the vertical magnet 53 is 105 magnetized each time. The current through the vertical magnet passes from ground G⁴ through the springs 105 and 104, conductor 106, private springs 107 and 108, conductor 109, side switch wiper 110, contact point 111, vertical magnet 53 to the battery lead 73, then through battery B to ground G. The 110 vertical magnet 53 upon operating twice raises the switch shaft 58 two steps and places the private and line wipers 59, 60 and 61 opposite the first contact of the second level of the private and line banks 62 and 63, respectively. After pressing the 115 vertical button the subscriber presses the rotary button 42 once, grounding the rotary line conductor 13. As a result the rotary line relay 52 of the connector is energized by a flow of current from the substation ground G¹ to the rotary line conductor 13, thence through the switch shaft springs 14 and 11 of the first-selector and through the bridge-cut-off relay springs 6 and 7 to the 120 side switch wiper 98, contact point 112, conductor 113, rotary wiper 32, trunk conductor 100, rotary line relay 52 to the battery lead 125 130

73 and through battery B to ground G. At the same time that the rotary line relay 52 is energized the rotary line relay 12 and the private normal relay 5 of the first-selector are energized also through the following circuit: From the substation ground G¹ to the line conductor 13, thence through the switch shaft springs 14 and 11 to the bridge-cut-off relay springs 6 and 7, thence through the conductor 80 to the rotary line relay 12, and to the battery lead 73, then through battery B to ground G. The said rotary line relay 12 upon attracting its armature presses the springs 17 and 18 into contact thereby sending a flow of current through the winding 15 of the private normal relay 5, as previously explained. Each time that the private normal relay 5 is energized the guarding potential established at the connector private banks by way of the private normal conductor 22 is cut off for an instant, but this is of no consequence yet. When the rotary line relay 52 attracts its armature the springs 114 and 115 are pressed together and also the springs 116 and 105. The connection of the former two (114 and 115) is of no consequence at this step, but the engagement of the springs 105 and 116 causes the private magnet 56 to become energized once. As a result the side switch I is tripped into second position. When the side switch is tripped into second position the side switch wiper 110 engages the contact point 117, so that the rotary magnet 54 instead of the vertical magnet 53 is placed under the control of the rotary line relay 51. For the last operation the subscriber presses the vertical button 41 ten times, grounding the vertical line conductor ten times and energizing (over circuits that have already been traced) the vertical line relay of the connector ten times. Each time that the vertical line relay presses the springs 104 and 105 into contact, since the side switch wiper 110 is now shifted as described, the rotary magnet 54 is operated. The current for magnetizing the said rotary magnet passes from ground G⁴ to the side switch wiper 110, as previously described, thence to the contact point 117, and through the rotary magnet 54 to the battery lead 73, then through battery B to ground G. The wipers 59, 60 and 61 having been previously raised to the second level are now rotated one step at a time and thus carried onto the tenth set of contacts and placed in connection with the normal conductors 22, 119 and 120, respectively, as shown in Fig. 1. It will be remembered that at the first-selector A the private normal conductor 22 is connected to ground G³ after the side switch passes to third position; therefore, the tenth contact 121 of the second level of the private bank 62 as well as all other connector private bank contacts in multiple therewith are grounded. Ordin-

narily upon grounding the rotary line conductor 13, after the private wiper 59 has been carried onto a grounded contact, the connector-switch is released. For example, when one subscriber's line calls another subscriber's line that is busy; but special provision is made in this case, so that a line may call back upon itself even after the first-selector has established a guarding potential, as described. This is accomplished by means of the private normal relay 5 that breaks the connection between the first-selector ground G⁸ and the private normal bank conductor 22 each time that the rotary line conductor 13 is grounded. When the subscriber presses the rotary button 42 for his last operation, by grounding the rotary line conductor 13 he energizes the first-selector rotary line relay 12 and, as a result, the private normal relay 5, as described. At the same time, and in multiple with the said rotary line relay 12, the rotary line relay 52 of the connector is energized over circuits that are known, and as a result the private magnet 56 is also energized. The private magnet 56 upon attracting its armature permits the escapement finger 122 to clear the tooth 123, and the side switch retracting spring 124 then draws the side switch I to third position before the private magnet deenergizes and before the private normal relay 5 deenergizes and restores the ground connection to the private contact point 121. If a guarding potential were not removed from the contact point 121, as in the case where one subscriber calls another subscriber whose line is busy, the release magnet 55 would be energized by a flow of current from the grounded terminal of the battery B to the private contact point with which the private wiper 59 is in contact, thence through the side switch wiper 125, contact point 126, conductor 127, line relay springs 114 and 115, conductor 128, release magnet 55 to the battery lead 73 and through battery B to ground G. The release magnet 55 then attracts its armature, releasing the shaft 58 and side switch I in the usual and well-known manner. As soon as the side switch passes to third position the side switch wiper 125 engages the contact point 129 and the private wiper 59 is placed in connection with the ground terminal G⁵. As a result the private normal conductor 22 is connected to ground from the opposite direction, and since the private normal relay springs 19 and 20 are now in contact the said relay 5 and the bridge-cut-off relay 2 are locked by the energizing current that flows from the said private normal conductor 22 through the said springs 20 and 19 to the winding 4 of the private normal relay 5, thence through the bridge-cut-off relay 2 to the battery lead 73 and 130

through battery B to ground G. As a result of energizing the bridge-cut-off relay 2 the vertical line relay 10 of the selector A is disconnected from battery B and the 5 rotary line relay 12 is disconnected from the rotary line 13, so that when ringing current is projected back on the line there will be no danger of these relays being energized and causing some interference with 10 the connection. It is also desirable, of course, to have the line as free of bridges as possible during talking. After establishing the connection the subscriber at the substation C presses the signaling button 130, 15 causing the spring 131 to leave the contact point 132 and to engage the grounded contact point 133. As a result the vertical line conductor 71 is grounded over the following circuit: from ground G¹ to the conductor 20 134, springs 135 and 136, ground springs 65 and 64, contact point 133, spring 131, secondary springs 69 and 70, contact point 45, spring 43 to the vertical line conductor 71 and, of course, the vertical line relay 25 51 of the connector becomes energized. Since the side switch wiper 110 is now in third position in engagement with the contact point 137, when the vertical line relay 51 becomes energized the ringer relay 30 57 responds. Magnetizing current passes from ground G⁴ to the side switch wiper 110, thence to the contact point 137 and through the relay 57 to battery lead 73, thence through battery B to ground G. 35 When the ringer relay becomes energized the springs 138 and 139 are pressed onto the ringer generator springs 140 and 141, respectively, so that a ringing current is sent back to the calling line over the following 40 circuit: from the ringer generator 142 through the ringer relay springs 141 and 139 to the side switch wiper 143, contact point 144, wiper 60, normal conductor 119 to the vertical line conductor 71, thence through 45 the ringers of various stations, whose receivers are on their hooks, back to the rotary line conductor 13, thence over the rotary normal conductor 120, rotary line wiper 61, contact point 145, side switch wiper 146, ringer 50 relay springs 138 and 140 to the ringer generator 142. The ringing current furnished by the ringer generator 142 is adapted to ring only the bell at the substation #226 and so that subscriber responds. It may be 55 stated that the connector switches are divided into groups and each group is connected with a ringer generator which provides a ringing current of a different frequency, so that when a subscriber of a certain group is 60 called the calling subscriber automatically selects a connector switch which is equipped with suitable ringing current for operating the ringer of the desired line only. The other ringers, however, which may be 65 bridged across the line are not operated,

since they are so tuned or adjusted as to respond to ringing current of a different character. When he removes his receiver his talking set is bridged across the vertical and rotary line conductors, just as the talking 70 set of the substation C and, of course, the two subscribers can then converse. After the conversation has terminated the calling subscriber may hang up his receiver and press the release springs 48, 49 and 50 of his 75 telephone together and thus ground the vertical and rotary line conductors 71 and 13 simultaneously, producing a release. The connection to the said line conductors is from ground G¹ through the substation release springs 135 and 136, ground springs 65 and 64 to the release spring 48, thence to the release springs 49 and 50 and to the rotary and vertical line conductors, respectively. Grounding the vertical and rotary line 80 conductors simultaneously produces an energization of the vertical and rotary back-bridge relays 147 and 148, respectively. The current for energizing the vertical back-bridge relay 147 flows from the vertical line 85 conductor 71 to the vertical normal conductor 119 (Fig. 1), thence to the vertical line wiper 60 (more clearly shown in Fig. 3) to the contact point 144, side switch wiper 143, ringer relay springs 139 and 149 to the vertical 90 back-bridge relay 147, thence to battery lead 73 and through battery B to ground G. The current for the rotary back-bridge relay 148 flows from the rotary line conductor 13 to the rotary normal conductor 120 (Fig. 1), 95 thence to the rotary line wiper 61 (Fig. 3) to the contact point 145, side switch wiper 146, ringer relay springs 138 and 150, through the rotary back-bridge relay 148 to the battery lead 73, and through battery B to ground G. Said relays upon attracting their armatures simultaneously press the springs 151, 152 and 153 into contact. The engagement of the springs 152 and 153 energizes the private magnet 56, the magnetizing current flowing from ground G⁶ through the springs 153 and 152, conductor 154 to the private magnet 56, thence through said magnet to the battery lead 73 and through 100 battery B to ground G. The private magnet upon becoming energized attracts its armature and separates the springs 108 and 107, whereby the energizing circuit through the ringer relay 57 is broken; bearing in mind that the vertical line relay 51 is also 105 energized at this time, which operates to close an energizing circuit through the ringer relay 57, as previously explained. The said spring 151 being now in engagement with the springs 152 and 153 a circuit is established through the release magnet 55 over which current flows for energizing the 110 said release magnet 55. The circuit extends from ground G⁶ through the springs 153, 152 and 151 to the conductor 156, release 115 120 magnet 55 and back to ground G. The circuit 125 extends from the conductor 156 through the release magnet 55 to the conductor 157, which is connected with the conductor 156, release magnet 55 and back to ground G. The circuit 130 extends from the conductor 157 through the release magnet 55 to the conductor 158, which is connected with the conductor 157, release magnet 55 and back to ground G.

magnet 55 to the battery lead 73, thence through battery B to ground G. The release magnet 55 upon becoming energized attracts its armature 157, which latter then 5 restores the double dog 158, and as a result the switch-shaft 58 and the side switch I are restored to normal position. As soon as the side switch wipers 143 and 146 leave the contact points 144 and 145 the 10 energizing circuit for the back release relays 147 and 148 is destroyed, so that the said relays 147 and 148 regain their normal condition, permitting the private magnet 56 and the release magnet 55 to regain their 15 normal condition also. It will also be understood that as soon as the side switch wiper 125 leaves the contact point 129 of the connector the circuit that has up to that time retained the private normal relay 5 of the 20 first-selector energized (which circuit includes the winding 4 of the relay 5 and the bridge-cut-off relay 2) is destroyed. As soon as the bridge-cut-off relay springs 6 and 7, and 8 and 9 reengage, the vertical 25 and rotary line relays 10 and 12 of the selector A will in turn become energized simultaneously. As a result of the energization of the rotary line relay 12 the springs 17 and 18 are brought into contact and the 30 private magnet 16 is also energized over circuits that have been described. Upon becoming energized the said private magnet separates the private springs 76 and 77 and presses the spring 77 into engagement with 35 the spring 159. The engagement of these last two springs 77 and 159 places the release magnet 25 in connection with the vertical line relay spring 74, so that as soon as the said spring 74 engages the spring 18 the 40 release magnet 25 becomes energized by a flow of current from the ground terminal G² through the private springs 77 and 159 and through the release magnet 25 to the battery lead 73 thence through battery 45 B to ground G. The release magnet 25 then attracts its armature 160, whereby the release link 161 latches the double dog 27, and when the release springs 48, 49 and 50 at the releasing substation disengage, the 50 vertical and rotary line relays 10 and 12 de-energize, deenergizing in turn the release magnet 25 and permitting the retracting spring 162 of the release armature 160 to restore the double dog 27 to normal condition, and as a result the switch-shaft 26 and 55 side switch H are also restored in a well known manner to normal condition. If a subscriber at the substation #320 attempts to use his 'phone while the subscribers C and D are using the line, the substation relay 163 becomes energized when the receiver 164 permits the switch-hook 165 to rise, and as a result the substation ground G² is cut off from the control of the substation E 60 when the springs 169 and 170 are separated.

The energizing current for the said relay 163 flows from ground G² through the springs 166 and 167, relay 163, springs 168 and 169 to the rotary line conductor 13, thence it passes to the rotary normal conductor 120 (Fig. 1), rotary line wiper 61 of the connector (Fig. 3), contact point 145, side switch wiper 146, ringer relay springs 138 and 150, rotary back-bridge relay 148 to the battery lead 73 and through battery 70 B to ground G. Before the connector F has made connection with the line the energizing circuit instead of extending over the rotary normal conductor 120, as described, passes through the switch shaft 75 springs 14 and 11 of the first-selector and through the bridge-cut-off relay springs 6 and 7 to the rotary line relay 12, thence through the said relay to the battery lead 73 and through battery B to ground G. It 80 will be seen that when the called subscriber raises his receiver, on answering, he will also be locked out, as shown, over circuits similar to those described in connection with station #320. By the term "locked out" is 85 meant that the locking relay 40 which controls the ground connection at the subscriber's substation becomes energized and operated to cut off the ground, thus rendering the telephone useless so far as the operation 90 of the central office switching apparatus is concerned. When the substation relay operates to break the substation ground connection, it may be restored when the subscriber restores his switch-hook. As a result the 100 link 40' depresses the substation relay armature, which latter then permits the controlled springs to be restored. It will be noticed that during the release—that is, when both the vertical and rotary line conductors are grounded simultaneously—a circuit is established through the vertical line relay 51 of the connector at the same time the circuit is established through the back-bridge relay 147, which circuit through the 105 vertical line relay 51 is already known. It might be expected that since the side switch wiper 110 is in third position the energizing of the said vertical line relay 51 might cause the energization of the ringer relay 57 in turn, 110 which latter would then break the energizing circuit for the back-bridge relays 147 and 148 by separating the ringer relay springs 138 and 139 from the ringer relay springs 150 and 149, but the relays and springs are so 115 adjusted that the back-bridge relays 147 and 148 respond much quicker than the vertical line relay 51 and much quicker than the ringer relay 57. Therefore, the release occurs before the ringer relay 57 has time to 120 energize. It will be clear from what has preceded that a connection may be made to another line by operating the switches in the same manner that has been described in the preceding, the only difference being 125 130

that instead of the normal conductors 119 and 120 leading back to the calling line they lead to some other subscriber's line, and in that event if the desired line is busy 5 the energization of the private normal 5, each time that the rotary line conductor 13 is grounded, will not remove the guarding potential from the called subscriber's private bank contact. Therefore, if the called line 10 should be busy the connector-switch F will be released, as already described. If the connection is established the calling subscriber will ring the desired line in the same manner that he rings his own line. It will 15 be understood that when the connector side switch passes to third position and the private wiper 59 is grounded, the private normal conductor that leads to the bridge-cut-off relay of the called first-selector will also 20 be grounded, and the said bridge-cut-off relay will be energized, thus removing the vertical and rotary line relays of the called first-selector from across the line. This relay 2 will be restored as soon as the connector-switch is restored, since when the said connector-shaft falls the ground connection is again removed from the private normal. If the called line should be another party line a third subscriber who attempts to use 25 the line from the side of the called line will be locked out, because his substation relay that controls the substation ground will become magnetized over the rotary normal conductor in the same manner that the substation relay 163 was shown to energize over the rotary normal conductor 120 (Fig. 1). On the other hand, if a third subscriber tries to interfere on the calling line (the substation E, for example), the relay 163 will 30 be energized not over the rotary normal 120 but by a new path which, after leaving the rotary line conductor 13, extends through the switch shaft springs 14 and 11, back-bridge relay springs 6 and 7, through the rotary line relay 12 to the battery lead 73 and through battery B to ground G. This path is available since the bridge-cut-off relay 2 is not energized because the line allotted to 35 the selector A is not being called and, therefore, the bridge-cut-off relay springs 6 and 7 are in contact as well as the switch shaft springs 14 and 11. The release, when two different lines are connected, may be initiated by the calling subscriber. When the calling subscriber releases he grounds his line conductors 71 and 13 and energizes the vertical and rotary line relays of the first-selector and the vertical and rotary line relays of the connector simultaneously over the circuits 40 that are known and which have been described. The first-selector will be released in a manner previously explained, and the connector will be released as follows: The line relay 52 upon energizing presses the 45 springs 114 and 115 into contact and also the springs 116 and 105 into contact. The latter two, as is well known, energizes the private magnet 56, which latter magnet then closes connection between the private springs 107 and 155. The closure of the springs 114 and 115 finally connects the release magnet 55 (since the private springs 107 and 155 are in contact) with the vertical line relay spring 104. The vertical line relay 51 being energized presses the spring 104 onto the spring 105, thus magnetizing the release magnet 55 by a flow of current from ground G* through the line relay springs 105 and 104, through the private springs 107 and 155, and through the rotary line relay springs 114 and 115 to 50 the release magnet 55, and through the said magnet to the battery B. As a result the connector side switch and shaft will be restored, and when the release springs at the releasing substation separate, all the relays 55 and magnets of the circuit that have been in use will regain normal condition.

In the first-selector the bridge-cut-off relay may be of any suitable resistance, but good results are obtained with a coil of thirteen hundred ohms. The private normal relay 5 gives satisfaction when the winding 4 is made of a resistance of five hundred ohms, and the winding 15 of two hundred and fifty ohms.

When one line is connected with another it is evident that the voice-currents pass through the condensers.

From the foregoing it will be seen that I provide improved means for enabling a party line subscriber to call back on his own line, so to speak, and for preventing the connector from being automatically released, the guarding potential being removed at the time that the connector seizes the normals leading from the line to the connector bank contacts.

It will be seen that the two line relays 10 and 12 of the first-selector are bridged across the subscriber's telephone line, but that the rotary relay has its end of the bridge normally disconnected from the said line, this normally open connection being closed by the contacts 11 and 14 of the normal post switch as soon as the selector is given the first vertical step. As previously explained, the private normal controlling relay 5 is double wound, and has one winding adapted to be energized in series with the bridge-cut-off relay 2, and has its other winding adapted to be energized over a separate circuit controlled by its own contacts.

What I claim as my invention is:—

1. In a telephone exchange system, a telephone line, a pair of relays bridged across the said line, a private normal for said line, a bridge-cut-off relay, a private normal relay controlling the continuity of said private normal, and a circuit for energizing the last-mentioned two relays in series.

2. An automatic telephone exchange system comprising a selector, trunk lines to be selected by said selector, means for causing said selector to perform a trunking operation in accordance with a digit of the called number, said selector provided with a bridge, a bridge-cut-off relay, a private normal, a private normal controlling relay, and a circuit for energizing said relays in series.
3. An automatic telephone exchange system comprising a subscriber's telephone line, an automatic switch individual to said line, said switch provided with a bridge, a bridge-cut-off relay, a private normal, a private normal controlling relay, and a circuit for energizing said relays in series.
4. An automatic telephone exchange system comprising a selector, trunk lines to be selected by said selector, means for causing said selector to perform a trunking operation in accordance with a digit of the called number, said selector provided with a bridge, a bridge-cut-off relay, a private normal, a private normal controlling relay, and a circuit for energizing said relays in series, said private normal relay provided with an additional energizing circuit, and said bridge including a relay controlling said additional energizing circuit.
5. An automatic telephone exchange system comprising a subscriber's telephone line, an automatic switch individual to said line, said switch provided with a bridge, a bridge-cut-off relay, a private normal, a private normal controlling relay, and a circuit for energizing said relays in series, said private normal relay provided with an additional energizing circuit, and said bridge including a relay controlling said additional energizing circuit.
6. An automatic telephone exchange system comprising a subscriber's telephone line, a private normal for said line, and an individual switch for said line, said individual switch provided with a private normal controlling relay having two windings, and parallel energizing circuits each including one of said windings, one of said energizing circuits controlled by the relay itself.
7. In a telephone exchange system, the combination of a telephone line, a pair of relays bridged across the said line, a private normal for said line, a bridge-cut-off relay, a private normal relay controlling the continuity of said private normal, a circuit for energizing the two relays in series, a bell or electric ringer at each substation, a source of ringing current at the exchange or central station, a ringer relay for bridging the source of ringing current across the line of any called substation, and a circuit for energizing said ringer relay after connection is established with the line of the called substation.
8. In an automatic telephone exchange system, the combination of a selector, trunk lines to be selected by said selector, means for causing said selector to perform a trunking operation in accordance with a digit of the called number, said selector provided with a bridge, a bridge-cut-off relay, a private normal, a private normal controlling relay, and a circuit for energizing said relays in series, a bell or electric ringer at each substation, a source of ringing current at the exchange or central station, a ringer relay for bridging the source of ringing current across the line of any called substation, and a circuit for energizing said ringer relay after connection is established with the line of the called substation.
9. In an automatic telephone exchange system, the combination of a subscriber's telephone line, an automatic switch individual to said line, said switch provided with a bridge, a bridge-cut-off relay, a private normal, a private normal controlling relay, and a circuit for energizing said relays in series, a bell or electric ringer at each substation, a source of ringing current at the exchange or central station, a ringer relay for bridging the source of ringing current across the line of any called substation, and a circuit for energizing said ringer relay after connection is established with the line of the called substation.
10. In an automatic telephone exchange system, the combination of a selector, trunk lines to be selected by said selector, means for causing said selector to perform a trunking operation in accordance with a digit of the called number, said selector provided with a bridge, a bridge-cut-off relay, a private normal, a private normal controlling relay, and a circuit for energizing said relays in series, said private normal relay provided with an additional energizing circuit, and said bridge including a relay controlling said additional energizing circuit, a bell or electric ringer at each substation, a source of ringing current at the exchange or central station, a ringer relay for bridging the source of ringing current across the line of any called substation, and a circuit for energizing said ringer relay after connection is established with the line of the called substation.
11. In an automatic telephone exchange system, the combination of a subscriber's telephone line, an automatic switch individual to said line, said switch provided with a bridge, a bridge-cut-off relay, a private normal, a private normal controlling relay, and a circuit for energizing said relays in series, said private normal relay provided with an additional energizing circuit, and said bridge including a relay controlling said additional energizing circuit, a bell or electric ringer at each substation, a source of ringing current at the exchange or central station, a ringer relay for bridging the source of ringing current across the line of any called substation, and a circuit for energizing said ringer relay after connection is established with the line of the called substation.

tral station, a ringer relay for bridging the source of ringing current across the line of any called substation, and a circuit for energizing said ringer relay after connection is 5 established with the line of the called substation.

12. In an automatic telephone exchange system, the combination of a subscriber's telephone line, a private normal for said line, and an individual switch for said line, 10 said individual switch provided with a private normal controlling relay having two windings, and parallel energizing circuits each including one of said windings, one of 15 said energizing circuits controlled by the relay itself, a bell or electric ringer at each substation, a source of ringing current at the exchange or central station, a ringer relay for bridging the source of ringing current 20 across the line of any called substation, and a circuit for energizing said ringer relay after connection is established with the line of the called substation.

13. In a telephone exchange system, the 25 combination of a telephone line, a pair of relays bridged across the said line, a private normal for said line, a bridge-cut-off relay, a private normal relay controlling the continuity of said private normal, a circuit for 30 energizing the two relays in series, and a ground connection at each substation, said ground connections normally disconnected from the telephone line conductors, but each ground connection adapted for use by its 35 allotted subscriber in performing a separate ground impulse transmitting operation for each digit of any called number.

14. In an automatic telephone exchange system, the combination of a selector, trunk 40 lines to be selected by said selector, means for causing said selector to perform a trunking operation in accordance with a digit of the called number, said selector provided with a bridge, a bridge-cut-off relay, a private 45 normal, a private normal controlling relay, and a circuit for energizing said relays in series, and a ground connection at each substation, said ground connections normally disconnected from the telephone 50 line conductors, but each ground connection adapted for use by its allotted subscriber in performing a separate ground impulse transmitting operation for each digit of any called number.

55 15. In an automatic telephone exchange system, the combination of a subscriber's telephone line, an automatic switch individual to said line, said switch provided with a bridge, a bridge-cut-off relay, a private 60 normal, a private normal controlling relay, and a circuit for energizing said relays in series, and a ground connection at each substation, said ground connections normally disconnected from the telephone line 65 conductors, but each ground connection adapt-

ed for use by its allotted subscriber in performing a separate ground impulse transmitting operation for each digit of any called number.

16. In an automatic telephone exchange 70 system, the combination of a selector, trunk lines to be selected by said selector, means for causing said selector to perform a trunking operation in accordance with a digit of the called number, said selector 75 provided with a bridge, a bridge-cut-off relay, a private normal, a private normal controlling relay, and a circuit for energizing said relays in series, said private normal relay provided with an additional energizing circuit, and said bridge including a relay controlling said additional energizing circuit, and a ground connection at each substation, said ground connections normally disconnected from the telephone line 80 conductors, but each ground connection adapted for use by its allotted subscriber in performing a separate ground impulse transmitting operation for each digit of any 85 called number.

17. In an automatic telephone exchange 90 system, the combination of a subscriber's telephone line, an automatic switch individual to said line, said switch provided with a bridge, a bridge-cut-off relay, a private 95 normal, a private normal controlling relay, and a circuit for energizing said relays in series, said private normal relay provided with an additional energizing circuit, and said bridge including a relay controlling 100 said additional energizing circuit, and a ground connection at each substation, said ground connections normally disconnected from the telephone line conductors, but each ground connection adapted for use by its allotted subscriber in performing a separate ground impulse transmitting operation for each digit of any 105 called number.

18. In an automatic telephone exchange 110 system, the combination of a subscriber's telephone line, a private normal for said line, and an individual switch for said line, said individual switch provided with a private 115 normal controlling relay having two windings, and parallel energizing circuits each including one of said windings, one of said energizing circuits controlled by the relay itself, and a ground connection at each substation, said ground connections normally disconnected from the telephone line 120 conductors, but each ground connection adapted for use by its allotted subscriber in performing a separate ground impulse transmitting operation for each digit of any 125 called number.

19. In a telephone exchange system, a telephone line, a pair of relays bridged across the said line, a private normal for said line, a bridge-cut-off relay, a private 130 normal relay controlling the continuity of

said private normal, a circuit for energizing the last-mentioned two relays in series, and means having non-rotary motion to select groups and then rotary motion to connect with the called line in any group selected by the non-rotary motion of the same means, both motions controlled over said telephone line from the substation thereof.

20. An automatic telephone exchange system comprising a selector, trunk lines to be selected by said selector, means for causing said selector to perform a trunking operation in accordance with a digit of the called number, said selector provided with a bridge across the conductors of the talking circuit, a relay in said bridge for controlling said selector, a bridge-cut-off relay, a private normal, a private normal controlling relay, and a circuit for energizing said relays in series, said selector having one motion to select groups, and then rotary motion to find a line in any selected group controlled by elements in said bridge.

21. An automatic telephone exchange system comprising a subscriber's telephone line, an automatic switch individual to said line, said switch provided with a bridge across the conductors of the talking circuit, a relay in said bridge for controlling said

switch, a bridge-cut-off relay, a private normal, a private normal controlling relay, and a circuit for energizing said relays in series, said selector having one motion to select groups, and then rotary motion to find a line in any selected group controlled by elements in said bridge.

22. An automatic telephone exchange system comprising a subscriber's telephone line, a private normal for said line, an individual switch for said line, said individual switch provided with a private normal controlling relay having two windings, parallel energizing circuits each including one of said windings, one of said energizing circuits controlled by the relay itself, and means having non-rotary motion to select groups and then rotary motion to connect with the called line in any group selected by the non-rotary motion of the same means, both motions controlled over said telephone line from the substation thereof.

Signed by me at Chicago, Cook county, Illinois, this 26th day of July, 1906.

WILSON L. CAMPBELL.
